UNITED STATES PATENT OFFICE.

ERNEST BÖHM, OF LONDON, ENGLAND.

PROCESS FOR PRODUCING LIGHT-TRANSMITTING OBJECTS.

No. 847,396.

Specification of Letters Patent.

Patented March 19, 1907.

Application filed April 30, 1906. Renewed February 12, 1907. Serial No. 357,058.

To all whom it may concern:

Be it known that I, ERNEST BÖHM, a subject of the King of Great Britain, and residing at London, England, have invented new and useful Improvements in Processes for Producing Light-Transmitting Objects, of which the following is a specification.

My invention relates to a process for producing light-transmitting objects—such as lamp bulbs, globes, shades, and the like—having superior light-transmitting and light-diffusing qualities, and consists in the successive steps hereinafter described, with the means illustrated in the drawings, which steps will be particularly pointed out in the claims.

The object of my invention is to provide a process by the use of which a plurality and multiplicity of individual and independent lenses may be formed integral with the walls of light-transmitting objects, such as a globe or bulb of an electric lamp, for the purpose of improving the illumination and the diffusion of light.

For the purpose of illustration I will describe my invention with particular reference to the production of incandescent electric-lamp bulbs; but it will be understood that other light-transmitting or light-diffusing objects may be formed similarly.

In the accompanying drawings, forming a part of this application, and in which like letters refer to corresponding parts, I have shown the parts with which I carry out my process and the product I obtain.

Figure 1 represents a side elevation of an ordinary glass tube from which smooth or common globes or bulbs are formed or blown. Fig. 2 represents different forms of rods, such as may be used, having bosses or notches for producing the irregular lens-surfaces herein-after mentioned. Fig. 3 represents the uniting of such a rod to a glass tube by winding it about the same. Fig. 4 represents a side view of a globe or bulb made in accordance with my process, showing a plurality and multiplicity of lenses and provided with an incandescent filament. Fig. 5 represents a bottom plan view of the globe or bulb manufactured by my process, showing in convolute lines a plurality and multiplicity of lenses on the same.

In making my lamp I take a glass tube A, preferably partly opal or colored, of the size and length usually employed in forming or blowing glass bulbs or globes for lamps and

wind spirally around, either inside or outside, rod or thread B, provided with notches, bosses, or swellings, round, oval, or oblong, said rod or thread B having been heated to a sufficient degree to render it pliable and easily bent, as shown in Fig. 3. The tube and rod thus wound are then heated to the required degree for blowing and are blown to any desired size. During the blowing operation the spirally-wound glass rod, with its bosses and swellings, is incorporated and blended with the tube and becomes an integral part thereof, making an irregularly-corrugated surface with a multitude of independent lenses formed in the globe by the breaking up and crossing of the surfaces of the tube and rod. These lenses will disseminate independent and distinct rays of light, and thus the light radiated from the globe is increased, diffused more perfectly than by ordinary lamps, and also the incandescent filament is hidden, and so does not dazzle the eyes.

I may employ my invention with plain tubes of glass or with tubes partly made of opal or colored glass.

I may use any of the various forms of rod B B' B'', &c., shown in Fig. 2, in the manner above described, using one or another, according to whichever is best adapted for the particular effect desired.

Having thus fully described my invention, what I claim, and desire to secure by Letters Patent, is—

1. The herein-described process of making light-transmitting and light-diffusing objects which consists in forming a rod having numerous surface irregularities or bulbs and uniting the same with a plain surface, substantially as described.

2. The herein-described process of forming or making light-transmitting and light-diffusing objects, which consists in winding upon a glass tube, a rod having numerous surface irregularities, raising the tube and rod to the required temperature for blowing, and blowing the bulb and rod to the desired shape and size, thereby forming on the surface of said globe a multiplicity of light-radiating lenses substantially as described.

In testimony whereof I affix my signature in presence of two subscribing witnesses.

ERNEST BÖHM.
